(57) **ABSTRACT**

A *chrysanthemum* plant named 'Zanmugolmine' characterized by its medium sized blooms with yellow ray florets and prolific branching; natural season flower date August 17 (week 34); blooming for a period of 5 weeks.

3 Drawing Sheets

1

Botanical designation: ***Chrysanthemum×morifolium***
Ramat.
Cultivar denomination: 'Zanmugolmine'.

BACKGROUND OF THE INVENTION

The present invention relates to a new and distinct cultivar of *chrysanthemum* plant, botanically known as *Chrysanthemum×morifolium* Ramat., commercially known as a garden mum, and hereinafter referred to by the cultivar denomination 'Zanmugolmine'. 'Zanmugolmine' is a product of a breeding and selection program for outdoor pot mums (garden mums) which had the objective of creating new cultivars with a double type inflorescence, a natural season flower date around August 17 (week 34), blooming for a period of 5 weeks. 'Zanmugolmine' is a seedling resulting from a cross of the female parent id 19268 with the male parent id 15038. Plants of the new cultivar 'Zanmugolmine' differ from plants of the female parent in the color of the ray-florets. The color is in the seedling yellow, while pink in the female parent.

Plants of the new cultivar 'Zanmugolmine' differ from plants of the male parent in the following characteristics. (1) Natural season flowering date. And (2) Inflorescence size. (1) Plants of the seedling flower earlier in the season than those of the male parent. (2) Inflorescences of the seedling are larger than those of the male parent.

The new and distinct cultivar was discovered and selected as a flowering plant by Wilhelmus Bernardus Blom on a cultivated field in Rijsenhout, The Netherlands in 2005. The first act of asexual production of 'Zanmugolmine' was accomplished when vegetative cuttings from the initial selection in 2005 were propagated further in a controlled environment in Rijsenhout, The Netherlands. The new cultivar has been found to retain its distinctive characteristics through successive propagations.

BRIEF DESCRIPTION OF THE DRAWINGS

The present invention of a new and distinct variety of *chrysanthemum* is shown in the accompanying drawings, the color being as nearly true as possible with color photographs of this type.

2

FIG. 1 shows a plant of the cultivar in full bloom.

FIG. 2 shows the various stages of bloom of the new cultivar.

FIG. 3 shows the various stages of foliage of the new cultivar.

DESCRIPTION OF THE INVENTION

10 The observations and measurements were gathered from plants grown out door in Rijsenhout, The Netherlands under natural day length and temperature and planted in week 23 in 2009. The natural blooming date of this crop was August 17
15 (week 34). The average height of the plants was 18 cm. No growth retardants were used. No tests were done on disease or insect resistance or susceptibility. No tests were done on cold or drought tolerance. This new variety produces medium
20 sized blooms with yellow ray florets blooming for a period of 5 weeks.

From the cultivars known to inventor the most similar existing cultivar in comparison to 'Zanmugolmine' is 'Zanmustone' (U.S. Plant Patent applied). When 'Zanmustone' and 'Zanmugolmine' are being compared the following difference is noticed: The differences of 'Zanmustone' and 'Zanmugolmine' are (1) Color ray-florets. And (2) Plant size (1) The ray-florets of 'Zanmugolmine' are less intensively yellow than those of 'Zanmustone'. (2) The plants of 'Zanmugolmine' are slightly smaller than those of 'Zanmustone'.

35 The following is a description of the plant and characteristics that distinguish 'Zanmugolmine' as a new and distinct variety.

The color designations are taken from the plant itself. Accordingly, any discrepancies between the color designations and the colors depicted in the photographs are due to photographic tolerances. The color chart used in this description is: The Royal Horticultural Society Colour Chart, edition 2001.

TABLE 1

Botanical Description of <i>Chrysanthemum xmorifolium</i> Ramat. 'Zanmugolmine'	
Bud	
Size	Small; cross-section 6 mm, height 7 mm
Shape	Round
Texture	Pubescent
Outside Color	Greyed-green 191A
Phyllaries	
Number	18, arranged in 3 rows
Shape	Elliptic
Apex	Acute
Base	Truncate
Margin	Entire
Color	Upper surface
Length and width	7 mm; 3 mm
Texture	Pubescent
Inflorescence	
Type	Double
Height	2 cm
Diameter	5 cm
Peduncle length	3 cm
Peduncle color	Greyed-green 191B
Peduncle diameter	1.8 mm
Peduncle texture	Pubescent
Number per branch	Approx. 5 inflorescences
Duration of flowering	5 weeks
Seeds	Produced in small quantities, ovate, Greyed-brown 199A, length 1.5 mm, diameter 0.5 mm
Fragrance	Faint <i>chrysanthemum</i> odor
Color	
Center of inflorescence (disc florets)	Immature stage: Yellow 13A Mature stage: Yellow 6A
Color of upper surface of the ray-florets	Yellow 8A
Color of the lower surface of the ray-florets	Yellow 10A
Tonality from Distance	A garden mum with yellow flowers
Color of the ray-florets after aging of the plant	Yellow 6C
Ray florets	
Texture	Upper and lower surface smooth
Number	Ca. 110
Shape	Elliptic
Apex	Pointed
Base	Attenuate
Cross-section	Concave
Longitudinal axis of majority	Straight
Length of corolla tube	5 mm
Ray-floret margin	Entire
Ray-floret length	2.5-3.5 cm
Ray-floret width	3-5 mm
Ratio length/width	High
Disc florets	
Disc diameter	1-2 mm
Distribution of disc florets	Few, only visible in mature age of the inflorescences
Shape	Funnel
Color	Yellow green 145C at base to Green yellow 1D at top
Length	4 mm
Receptacle	
Color	Yellow-green 145D
Shape	Domed raised
Height	5 mm
Diameter	3 mm

4

TABLE 1-continued

Botanical Description of <i>Chrysanthemum xmorifolium</i> Ramat. 'Zanmugolmine'		
5 Reproductive Organs		
Androecium	Present on disc florets only	
Stamen length	3 mm	
Stamen color	Yellow-green 144A	
Anther color	Green-yellow 1A	
10 Pollen	Present	
Pollen color	Yellow 13A	
Gynoecium	Present on both ray florets and disc florets	
Style color	Yellow-green 154C	
Style Length	3 mm	
Stigma color	Yellow 7A	
15 Stigma Width	1 mm	
Ovary	Enclosed in calyx	
Plant		
Form	Grown as a spray type pot mum, outdoor raised and mounded	
20 Growth habit	Spherical shape	
Growth rate	Moderate	
Height	18 cm	
Width	25 cm	
Stem Color	Greyed-brown 199A	
25 Stem Strength	Medium	
Stem Brittleness	Brittle	
Stem Anthocyanin Coloration	Not observed	
Internode length	1-2.5 cm	
Length of lateral branch	From top to bottom 14-15 cm	
Lateral branch diameter	2 mm	
Lateral branch color	Green 137C	
30 Lateral branch, attachment	Brittle	
Branching (average number of lateral branches)	Prolific with 8 breaks after pinching	
Natural season blooming date	August 17 (week 34)	
Foliage		
35 Leaf color	Upper side: Green 137A Lower side: Green 138A	
Color midvein	Upper side: Yellow-green 147D Lower side: Yellow-green 148D	
Size	Small; length 3-4 cm, width 1.8-2.7 cm	
Quantity (number per lateral branch)	14-16	
40 Shape	Broadly elliptic	
Texture upper side	Sparingly pubescent	
Texture under side	Pubescent	
Venation arrangement	Palmate	
Shape of the margin	Serrated	
Shape of Base of Sinus	Rounded	
45 Between Lateral Lobes	Margin of Sinus Between	
Lateral Lobes	Converging	
Shape of Base	Attenuate	
Apex	Mucronulate	
Petiole length	0.5-1 cm	
50 Petiole diameter	1.5-2 mm	
Petiole color	Yellow-green 147D	
55 Differences with the comparison variety (when grown side to side)		
	"Zanmugolmine" "Zanmustone"	
Color upper surface ray-florets	Yellow 8A	Yellow 7A
Plant height	18 cm	20 cm
I claim:		
1. A new and distinct <i>chrysanthemum</i> plant named 'Zanmugolmine' as described and illustrated.
